(57) **CLAIM**

The ornamental design for a sterilizing cleaner, as shown and described.

DESCRIPTION

FIG. 1 is a front perspective view of the sterilizing cleaner showing our new design in hidden state when the claimed design does not operate;

FIG. 2 is a front view thereof where the back view is a mirror image;

FIG. 3 is a left side view thereof;

FIG. 4 is a right side view thereof;

FIG. 5 is a top plan view thereof;

FIG. 6 is a bottom plan view thereof;

FIG. 7 is a front perspective view thereof in a condition that the cleaner is protruding after being operated;

FIG. 8 is a front view of FIG. 7 where the back view is a mirror image;

FIG. 9 is a left side view of FIG. 7;

FIG. 10 is a right side view of FIG. 7;

FIG. 11 is a top plan view of FIG. 7;

FIG. 12 is a bottom plan view of FIG. 7;

FIG. 13 is a front perspective view thereof in a condition that the intermediate state of cleaning;

FIG. 14 is a front view of FIG. 13 where the back view is a mirror image;

FIG. 15 is a left side view of FIG. 13;

FIG. 16 is a right side view of FIG. 13;

FIG. 17 is a top plan view of FIG. 13;

FIG. 18 is a bottom plan view of FIG. 13;

FIG. 19 is a front perspective view thereof in a condition that the final state of cleaning;

FIG. 20 is a front view of FIG. 19 where the back view is a mirror image;

FIG. 21 is a left side view of FIG. 19;

FIG. 22 is a right side view of FIG. 19;

FIG. 23 is a top plan view of FIG. 19; and,

FIG. 24 is a bottom plan view of FIG. 19.

(Continued)

The broken lines depict portions of the sterilizing cleaner that form no part of the claimed design.
